UNITED STATES PATENT OFFICE.

JOSEPH BREEN, OF AMBRIDGE, PENNSYLVANIA.

PUSHER FOR TIN POTS.

Application filed February 16, 1922. Serial No. 536,887.

To all whom it may concern:

Be it known that I, JOSEPH BREEN, residing at Ambridge, in the county of Beaver and State of Pennsylvania, a citizen of the 5 United States, have invented or discovered certain new and useful Improvements in Pushers for Tin Pots, of which improvements the following is a specification.

My invention relates to pushers for tin 10 pots. A pusher is an instrument which the attendant of a tin pot holds. He feeds the uncoated plates one by one into the bath of molten tin in the tin pot. He thrusts the plate downward and edgewise into the pot 15 and then applying his pusher to the rear edge drives it deeper into the bath, submerging it entirely and forcing it forward through an upwardly curving path (defined by means not necessary here to describe) 20 into the bite of a pair of rolls which carry the sheets from the bath again.

The pusher ordinarily is a mere rod with a crotched end. In the ordinary run of the mill a certain appreciable percentage of 25 plates are found to be damaged by the pushing instrument. Some of this damage is due to careless use of the instrument and is avoidable, some is not. I have designed a pusher in the use of which the element 30 of damage, both the avoidable and the unavoidable part as well, is very considerably reduced. Furthermore the pusher of my invention is more easily made, as a matter of blacksmith work, than the less satisfactory pusher in general use.

The pusher of my invention is shown in side and rear elevation in the two figures of the accompanying drawings;

Fig. 1 being the side elevation,
40 Fig. 2 being the rear elevation.

As with the usual pusher mine is made from a single length of rod 1, pointed at the rear end for application of a handle.

The forward end is by the blacksmith 45 first forged flat with tongue-shaped tip, then the flattened end is shaped to the particular configuration best shown in Fig. 1. The features of this configuration may be noted in order from rear to forward end, thus,— 50 first, an arc-shaped length *a*, of some 60° extent, more or less, on a radius of an inch and a half, more or less; second, a sharp turn *b*; third, a second arc-shaped length *c*, approximating parallelism with length *a* 55 but diverging slightly from *a*; fourth, a

round bottomed turn *d*; ending in, fifth, the tongue *e*.

The features of improvement over the usual crotched bar are, first, the round-bottomed turn *d*, adapted to engage the edge 60 of the plate. Though the user may thrust forward with considerable force, in order to carry the forward edge of the plate into the bite between the rolls above referred to, still the plate cannot jam and be caught 65 in the notch in the pusher. Second, in the downward thrust it is the portion *c* of the pusher which overlies the surface of the plate adjacent the edge. As the plate advances along its upwardly curved path this 70 surface *c* will bear to greater or less extent upon the surface of the plate. But as this occurs the surface of contact is by the curved shape of this portion of the pusher extended. With the ordinary pusher the corresponding 75 surface is flat, and the tip of the prong (particularly if the instrument be carelessly used) is apt to dent and mar the plate. Third, the folding of the body of the pusher upon itself, in the two slightly diverging 80 lengths *a*, *c*, connected at *b*, gives to the instrument a springiness under strain of service which the usual pusher does not possess. And in this springiness is further prevention, against marring of the plate. A 85 fourth advantage has been noted: my instrument may be more cheaply made than the usual pusher and when made is more surely free of defect.

Automatic feed is largely used, but automatic apparatus at best must be made to take care of the material chiefly produced. Material which in thickness is greater or less than the range for which the machine is adapted, or differing greatly in surface 90 dimensions from what the machine is intended to deal with, must be pushed by hand, and hand pushing is by no means supplanted, even in plants equipped with 95 mechanical pushers.

I claim as my invention:

1. A tin-pot pusher consisting of a single length of metal rod bent at its tip to form a plate-engaging notch, said notched tip being continuous with the body of the instrument through an intermediate resilience-affording portion, substantially as described. 105

2. A tin-pot pusher consisting of a single length of metal rod formed at its tip to a plate-engaging notch, and adjacent said 110

notch formed to a convex plate-opposing surface, substantially as described.

3. A tin-pot pusher formed of a single length of rod formed at its tip to a plate-engaging notch d , said notched tip being continuous with the body of the instrument through an intermediate portion bent upon itself into a resilient fold, substantially as described.

10 4. A tin-pot pusher formed from a single

length of rod flattened and provided with tongue-shaped tip, the flattened portion being first shaped to a curved length a , bent back upon itself in a turn b , continuing in a second curved length c diverging slightly 15 from length a , and terminating in a round-bottomed notch d , substantially as described.

In testimony whereof I have hereunto set my hand.

JOSEPH BREEN.
